Fig. 2

Fig. 3

Fig. 4

Fig. 5

Fig. 6

Fig. 7

The essential features of the design reside in the portions shown in solid lines.

I claim:

The ornamental design for a bar of soap, as shown and described.
